INFANT'S AND CHILD'S RESTRAINING
JACKET

Horace L. Newman, New York, N. Y.

Application January 17, 1933. Serial No. 652,207

7 Claims. (Cl. 128—134)

This invention relates to apparel and more particularly to a restraining garment for infants and children. One object of the invention is to provide a garment of this character which will 5 serve very effectively to prevent an infant or child from scratching its face or sucking its thumb without being uncomfortable when worn.

Another object of the invention is to provide a restraining garment which may take the form 10 of a night gown, shirt or dress having sleeves which are of greater length than the arms of a child wearing the garment and have their outer free end portions so constructed that the hands will be entirely enclosed within the sleeves and 15 the child prevented from scratching its face or sucking its thumb.

A still further object of the invention is to provide the outer ends of the sleeves with cuffs of 20 such construction that stiffening sheets may be inserted to prevent a child from placing its thumb together with a portion of the sleeve or cuff into 25 its mouth or using its hands to scratch even if enclosed in long sleeves.

Another object of the invention is to provide 30 stiffening sheets which can be easily inserted or removed and thereby permit removal of the stiffening sheets when the garment is to be laundered while at the same time so constructing the stiffening sheets that they will be frictionally held 35 within the cuffs and cause the cuffs to be bulged outwardly from the sleeves and afford ample room for the child or infant to freely move its hands. Therefore, the child will not be inconvenienced by having its hands confined in a small space and 40 prevented from sleeping comfortably.

With these and numerous other objects in view, 45 my invention consists in the novel features of construction, combination and arrangement of parts as will be hereinafter referred to and more particularly pointed out in the specification and claims.

In the accompanying drawing forming a part 50 of this application:

Figure 1 is a view of a restraining garment constructed in accordance with this invention;

Figure 2 is an enlarged view in elevation showing a portion of one sleeve and a stiffening sheet and illustrating the difference in width between the sheet and the cuff into which it fits;

Figure 3 is a side elevation showing the stiffening sheet within the cuff;

Figure 4 is a view taken at right angles to Figure 3;

Figure 5 is an enlarged sectional view taken 55 along the line 5—5 of Figure 3;

Figure 6 is a sectional view taken along the line 6—6 of Figure 5;

Figure 7 is a perspective view of one of the stiffening sheets.

In describing my invention, I shall refer to the 60 drawing in which similar reference characters designate corresponding parts throughout the several views.

Infants and many children have the habit of sucking their thumbs during the day or when 65 they are asleep and also infants often scratch their faces as it is difficult to keep their nails properly cut. Sucking the thumb is a very bad habit as it causes mouth breathing and adenoids and in addition pressure exerted by a thumb 70 placed in an infant's mouth will distort the upper or lower jaw bone and not only spoil the shape of the mouth but also cause protruding teeth.

In order to overcome this habit of thumb sucking and prevent an infant from scratching its 75 face, I employ a garment 1 which may be a night-gown, shirt, dress or similar garment and which is made with sleeves 2 of such length that they extend beyond the hands as shown in Figure 5. The sleeves each consists of front and rear sections 3 having their side edges and the marginal edges at their outer ends sewed to form an inwardly extending seam 4 firmly uniting the sections and thereby providing the sleeves with 80 closed outer ends so that the child or infant can 85 not thrust its hands outwardly through the sleeves.

Cuffs 5 are provided for at the outer end portions of the sleeves and each cuff is formed of 90 fabric sections 6 of the same material from which the sleeves and body of the garment are made. These sections are disposed against front and rear portions of the sleeves and have their marginal portions folded into the seam 4 and secured therein as shown at 7 when the seam 4 is sewed. 95 The cuff forming sections are firmly sewed along their sides and outer ends but their inner ends are free and provide entrances to pockets 8 having the cuff sections serving as their outer walls and the covered portions of the sleeves 100 forming their inner walls. Before being applied to the sleeves the cuff forming sections have their rear end portions folded inwardly to form flaps 9 serving to reinforce the outer walls of the pockets and also providing finished edges for the cuffs and 105 permitting stiffening sheets to be easily inserted or withdrawn from the pockets.

The stiffening sheets 10 are formed of celluloid and are initially flat but since they are formed of flexible material, they may be bowed 110

transversely as shown in Figure 6 when thrust into the pockets. The stiffening sheets fit snugly into the pockets with their edges in frictional binding engagement with margins of the pockets 5 to prevent them from sliding freely and accidentally slipping out of the pockets and referring to Figure 2, it will be seen that the width of the stiffening sheet indicated by the line B is somewhat greater than the width of the pocket indicated by the line A and therefore the stiffening sheets must be bowed in order to insert them 10 and will retain their bowed condition when in place. This will cause walls of the pockets to be bulged outwardly and ample room will be provided 15 within the sleeve to permit the child to freely move its hands without binding due to pressure. In order to more effectively cause frictional grip upon side edges of the stiffening sheets, the stitching may be offset as shown at 11 in Figure 2, 20 thereby providing opposed inwardly projecting portions which firmly grip the sheets from opposite sides thereof and not only insure bowing of the same but also make it necessary to exert a certain amount of force in order to insert or 25 withdraw the sheets and prevent them from working out of the pockets.

When this garment is in use, it is put on the child in the same manner in which a dress or nightgown is donned. The stiffening sheets may 30 be inserted either before or after the garment has been put on and when in place serve to hold the closed outer end portions of the sleeves spaced from the child's hands and permit the child to move its hands freely. The fact that the cuffs 35 and outer end portions of the sleeves are stiffened by the sheets 10, prevents the child from scratching its face and also prevents the child from putting its thumb together with a portion of the sleeve and cuff into its mouth. A child will thus 40 be broken of the thumb sucking habit and also prevented from scratching its face and disfiguring its face. The device will be particularly effective in preventing a child scratching if afflicted with eczema upon its face or other portions 45 of the body. When the garment is to be laundered, the stiffening sheets can be easily and quickly removed so that they will not be damaged or interfere with proper washing of the sleeves by hand or in a washing machine.

50 From the above description of my improved garment, it will be seen that I have provided a simple, inexpensive and efficient means for carrying out the objects of the invention.

55 While I have particularly described the elements best adapted to perform the functions set forth, it is obvious that various changes in form, proportion and in the minor details of construction may be resorted to without departing from the spirit or sacrificing any of the principles of 60 the invention.

Having thus described the invention, what is 65 claimed is:

1. A restraining garment for infants and children, said garment having sleeves closed at their 65 outer ends, cuffs for said sleeves forming pockets open at their inner ends, and stiffening means in said pockets disposed about portions of the sleeves surrounding a person's hands when the garment is worn.

70 2. A restraining garment for infants and children, said garment having sleeves of a length to extend beyond the hands of a person wearing the garment, said sleeves being closed at their outer ends to confine the hands, cuffs fitting about the outer end portions of said sleeves and defining

pockets open at their inner ends, and stiffening sheets fitted into said pockets and removable through the open inner ends thereof, said sheets being disposed about portions of the sleeves surrounding the hands.

80 3. A restraining garment for infants and children, said garment having sleeves of a length to extend beyond the hands of a person wearing the garment, said sleeves being closed at their outer ends to confine the hands, cuffs fitting about the outer end portions of said sleeves and defining pockets open at their inner ends, and removable stiffening sheets fitted into said pockets through the inner ends thereof and disposed about portions of the sleeves surrounding the hands, said sheets being bowed transversely when in place and serving to permit free movement of a person's hands and prevent crumpling of the sleeves and cuffs.

85 4. A restraining garment for infants and children, said garment having sleeves of a length to extend beyond the hands of a person wearing the garment, said sleeves being closed at their outer ends to confine the hands, cuffs fitting about the outer end portions of said sleeves and 90 sewed along outer ends and opposite sides of the sleeves to define opposed pockets open at their inner ends, and stiffening sheets of flexible material fitted into said pockets through the open inner ends thereof and having binding fit 105 therein, the stiffening sheets being disposed about portions of the sleeves surrounding the hands.

95 5. A restraining garment for infants and children, said garment having sleeves of a length to extend beyond the hands of a person wearing the garment, said sleeves each consisting of front and rear sections having their side edges and outer marginal edges sewed together to form a sleeve closed at its outer end, cuffs for said sleeves 110 consisting of front and rear sections having their side edges and outer ends sewed into the seams uniting front and rear sections of said sleeves, said cuff sections defining pockets open at their inner ends and stiffening sheets fitted into said 115 pockets through their open rear ends and having binding fit therein, the stiffening sheets being disposed about portions of the sleeves surrounding the hands.

120 6. A restraining garment for infants and children, said garment having sleeves of a length to extend beyond the hands of a person wearing the garment, said sleeves each consisting of front and rear sections having their side edges and outer marginal edges sewed together to form 125 a sleeve closed at its outer end, cuffs for said sleeves consisting of front and rear sections having their side edges and outer ends sewed into the seams uniting front and rear sections of said sleeves, said cuff sections defining pockets open 130 at their inner ends and stiffening sheets fitted into said pockets through their open rear ends and disposed about portions of the sleeves surrounding the hands, the stiffening sheets being initially flat and of slightly greater width than the pockets whereby the sheets when in place within the pockets will be bowed transversely and cause the cuffs to bulge transversely about the sleeves.

135 7. A restraining garment for infants and children, said garment having sleeves of a length to extend beyond the hands of a person wearing the garment, said sleeves each consisting of front and rear sections having their side edges and outer marginal edges sewed together to form 140

a sleeve closed at its outer end, cuffs for said sleeves consisting of front and rear sections having their side edges and outer ends sewed into the seams uniting front and rear sections of said sleeves, said cuff sections defining pockets open at their inner ends and inner end portions of the cuff sections being turned inwardly, and stiffening sheets fitted into said pockets through their open rear ends and having binding fit therein, the stiffening sheets being disposed about portions of the sleeves surrounding the hands. 80
